(57) CLAIM

The ornamental design for a formed pliers/tool holster, as shown.

DESCRIPTION

FIG. 1 is a front elevation view of the formed pliers/tool holster showing my new design;

FIG. 2 is a left side elevation view thereof;

FIG. 3 is a top plan view thereof;

FIG. 4 is a rear elevation view thereof;

FIG. 5 is a right side elevation view thereof;

FIG. 6 is a bottom plan view thereof;

FIG. 7 is a front elevation view of a second embodiment;

FIG. 8 is a left side elevation view thereof; and,

FIG. 9 is a top plan view thereof.

The broken line showing pliers assembly is for illustrative purposes only and forms no part of the claimed design.
